UNITED STATES PATENT OFFICE

153,962

DESIGN FOR AN ASH TRAY

Charles Mankouski, Newport, N. Y.

Application January 27, 1947, Serial No. 136,460

Term of patent 14 years

(Cl. D85—2)

To all whom it may concern:

Be it known that I, Charles Mankouski, a citizen of the United States, residing at Newport, in the county of Herkimer and State of New York, have invented a new, original, and ornamental Design for an Ash Tray, of which the following is a specification, reference being had to the accompanying drawing, forming part thereof.

Figure 1 is a plan view.

Figure 2 is a side view of an ash tray, showing my new design.

I claim:

The ornamental design for an ash tray, as shown.

CHARLES MANKOUSKI.
